UNITED STATES PATENT OFFICE.

JOHN HARVEY PEARSON, OF INDIANAPOLIS, INDIANA, ASSIGNOR TO ONEPIECE BIFOCAL LENS COMPANY, OF INDIANAPOLIS, INDIANA, A CORPORATION.

TORIC-TOOL PROTRACTOR.

1,356,656.

Specification of Letters Patent. Patented Oct. 26, 1920.

Application filed November 26, 1918. Serial No. 264,190.

To all whom it may concern:

Be it known that I, JOHN HARVEY PEARSON, a citizen of the United States, and a resident of Indianapolis, county of Marion, 5 and State of Indiana, have invented a certain new and useful Toric-Tool Protractor; and I do hereby declare that the following is a full, clear, and exact description thereof, reference being had to the accompanying 10 drawings, in which like letters refer to like parts.

The object of this invention is to effect a proper setting or adjustment of toric tools for grinding cylinders and compound lenses. 15 It is necessary for accurate and satisfactory work that the toric tools be set at the axes called for in the prescription.

The device is for the accurate mounting of toric tools, preferably two tools, in a tool holder at the proper axes with reference to 20 the tool holder, and after the tools are set in the tool holder, it is readily removable from the protractor and placed in a machine for grinding lenses with said tools. The 25 protractor is a separate device and independent of the grinding machine and its only function is for the setting and adjustment of the toric tools in the tool holder.

The chief feature of the invention consists 30 in mounting the tool holder in connection with a device having indicated on it a protractor for giving axes and mounting the toric tool in such holder adjacent said protractor scale and when the toric tool is 35 adjusted so that the axis marked on said tool will register with the proper axis called for by the prescription, as indicated on the protractor, and then clamping the toric tool tightly in said holder so that when the 40 holder is put in place in the machine for grinding the lenses, the toric tool is set with absolute accuracy for giving to the lens the proper axis.

The full nature of the invention will be 45 understood from the accompanying drawings and the following description and claims:

In the drawings, Figure 1 is a plan view 50 of the machine. Fig. 2 is a front elevation thereof. Fig. 3 is a vertical transverse section on the line 3—3 of Fig. 2. Fig. 4 is a similar section on the line 4—4 of Fig. 2.

The protractor device consists of a frame having a base 10 whereby the device can be 55 readily set on a table or stand and at the

rear side of said base a wall or plate 11 extends vertically for the entire length of the base 10 and is centrally reinforced by a vertical rib 12. The rib 12 is widened at its upper end to form a widened and forwardly 60 extending lug 13 from which a threaded clamping bolt 14 projects forwardly. Near each side of the plate 11 there is also another forwardly extending lug 15, as seen in Fig. 4, from which a headless pin 16 projects forwardly, the protruding portion thereof not being threaded so that these two lateral pins serve only as stop or supporting pins. On the rear of the upright frame or plate 11 there is a vertically extending 70 guide projection 17, see Fig. 3, and from the upper end of said guide there is a threaded bolt 18 projecting rearwardly. This bolt is in the same vertical plane as the bolt 14, but is on a little higher level than 75 said bolt 14, as seen in Fig. 3.

A top scale plate 20 made of relatively thin metal is secured by screws 21 along its rear edge to a vertical supporting plate 22, see Figs. 3 and 4, which has a central vertical slot 23 for the bolt 18 to extend through and at its center said plate 22 has a vertically disposed thickened portion 24. A washer 25 and nut 26 on bolt 18 enables the plate 22 to be vertically adjusted as desired. 85

The device which is shown herein is for adjusting two toric tools at a time and, therefore, the scale plate 20 has two semi-circular recesses 30 in its forward side of the proper size to receive the toric tool 31. 90 Around the margin of said semi-circular recess 30 there is a protractor scale 32 indicating 180 degrees and having numerals indicating said degrees.

The toric tools are made in the usual form 95 and have central downwardly extending shanks 35 adapted to be inserted in a vertical hole 36 in a tool holder 37. The tool holder herein shown, as seen in Fig. 3, is a bar with two of the vertical holes 36, 100 one near each end so that said holder carries two tools, one near each end, and the holder has near each end a set screw 38 for securing the tools in said holder when properly adjusted. At the center of the 105 holder 37 there is a vertical slot 40 with a rounded upper surface so that it fits astride the bolt 14 extending centrally and forwardly from the main frame. On said bolt 14 there is a washer 41 and a nut 42 for 110

- clamping the holder in position in the device so that the toric tools will fit in the recesses 30 of the protractor or scale plate 20. The scale plate is vertically adjusted and set so that it will be substantially flush with the upper edge of the tools when the tools are mounted in the manner described. The tool holder at each end rests directly upon the pin 16 so that there is no opportunity 5 for the tool holder to be inaccurately placed or displaced. With this arrangement it is very easy to mount the tool holders and the tools in the machine with absolute accuracy.
- 10 Each tool has an axis mark 50 on its margin and that mark has been made with particular reference to the surface which has been ground on the tool and also with the lenses to be ground by the tool. Such 15 a lens 51 is indicated by dotted lines in Fig. 1, and said axis mark 50 indicates not only the axis of the tool but also of the lens.
- 20 The tools are mounted loosely in the holder before they are set and then they are turned and are adjusted angularly until the axis mark 50 registers with the proper scale mark and degree called for by the prescription for the axis of the lens. Thus if 25 the prescription calls for an axis of zero or 180 degrees, the tool will be adjusted, as shown at the left-hand end of Fig. 1. If the tool for the other lens calls for an axis of 50 degrees, it is set with the axis mark 30 at 50 degrees. Then the set screws 38 are tightened until the tools are tightly secured in the holder. The holder is now ready to be removed by releasing the nut 42 and washer 41 and taken from this apparatus 35 and mounted in the grinding machine which may be of any usual type. Thus the relation of the tool to the holder is absolutely and accurately fixed by this protractor so that the axis of the lens will be accurately 40 produced.
- 45 The invention claimed is:

1. A protractor for the mounting of toric tools in tool holders, including a frame in connection with which the toric tool holder 50 is removably mounted, and a graduated plate vertically adjustable on said frame to bring the graduated portion thereof into proximity with the periphery of the surface of a toric tool in such holder, whereby the 55 tool can be mounted in the holder with its axis in a desired position.
2. A protractor for the mounting of toric tools in tool holders, including a frame in connection with which the toric tool holder

is removably mounted, a plate having a 60 graduated surface curved so as to be in close proximity with a portion of the circular periphery of the surfacing part of a tool, whereby the tool can be adjusted in its holder at the proper axis, and means for 65 adjusting the position of said plate on the frame to accommodate it to different tools and holders.

3. A protractor for the mounting of toric tools in tool holders, including a frame in 70 connection with which a toric tool holder is removably mounted which is adapted to hold simultaneously a plurality of toric tools, and a plate having a corresponding plurality of graduated and curved surfaces 75 adapted to conform to the curvatures of the toric tools and be located near their peripheries.

4. A protractor for the mounting of toric tools in tool holders, including a frame, a 80 plate mounted thereon with two graduated surfaces, means projecting from said frame substantially midway between said graduated surfaces on which a holder for a pair of toric tools is adapted to be removably 85 secured, and means on said frame for engaging and holding the ends of said tool holder in position.

5. A protractor for the mounting of toric tools in tool holders, including a frame, a 90 plate mounted thereon with two graduated surfaces, means projecting from said frame substantially midway between said graduated surfaces on which a holder for a pair of toric tools is adapted to be removably 95 secured, means on said frame for engaging and holding the ends of said tool holder in position, and means for vertically adjusting said plate in order to bring it substantially in the same plane as the surfacing 100 portions of the tools.

6. A protractor for the mounting of toric tools in tool holders, including a frame, a scale plate with two semi-circular recesses therein graduated from zero to 180 degrees, 105 means for adjustably mounting said plate in connection with said frame, means projecting from the frame opposite a point between said semi-circular recesses for securing a toric tool holder midway its ends, 110 and adapted to carry a toric tool on each end and means on the frame opposite each graduated recess for engaging and holding the ends of the tool holder so that the tools will be held in said graduated recesses. 115

In witness whereof, I have hereunto affixed my signature.

JOHN HARVEY PEARSON.
